UNITED STATES PATENT OFFICE.

WILLIAM A. TURBAYNE, OF LANCASTER, NEW YORK, ASSIGNOR TO GOULD COUPLER COMPANY, A CORPORATION OF NEW YORK.

CAR-LIGHTING SYSTEM.

No. 886,445.

Specification of Letters Patent.

Patented May 5, 1908.

Application filed June 20, 1906. Serial No. 322,515.

To all whom it may concern:

Be it known that I, WILLIAM A. TURBAYNE, a citizen of the United States, and a resident of Lancaster, in the county of Erie, State of New York, have invented certain new and useful Improvements in Car-Lighting Systems, of which the following is a specification.

My invention relates to car lighting systems in which a main dynamo is provided 10 driven in a suitable manner from the car, while a storage battery is connected across the terminals of the dynamo. In these systems it is impossible to maintain a uniform voltage across the terminals of the dynamo 15 or the terminals of the battery, because the dynamo is subjected to very wide variations of speed and because the battery voltage must change in order that it may at times be charged. For this reason it is necessary to 20 provide that the fluctuations of voltage of the system shall be eliminated or at least reduced substantially at the lamp terminals in the main circuit.

My invention consists in a car-lighting system employing, in combination with the usual dynamo and battery, a crusher placed 25 between the battery and the lamp circuit and regulated by a variable speed apparatus whose speed varies in accordance with 30 changes of voltage and by such variation of speed producing greater changes of voltage than those occurring across the dynamo or battery circuit. To this end I employ a motor connected across the dynamo circuit and 35 designed so that its speed will vary in substantial accordance with the variation of the dynamo voltage and I mechanically connect to this motor both the crusher and an exciter for the crusher, which exciter is so arranged 40 that it gives an electro-motive-force which increases in greater ratio than the change of speed of the exciter. Preferably, I also drive the crusher by the same motor. By this arrangement I am enabled to increase 45 the opposing electro-motive-force of the crusher to exactly the same extent as the voltage at the battery terminals increases, thus maintaining a constant voltage in the main circuit in which the lamps are situated.

The drawing accompanying this specification indicates diagrammatically a car lighting system embodying my invention.

A is the main dynamo driven in any suitable manner (not here shown) from the car 50 axle or other moving part of the car.

A' represents a field winding which may be regulated in any convenient manner to maintain as nearly uniform a voltage as can be maintained, or as the necessity for charging the battery will permit. A very desirable 60 method for regulating the dynamo has been set out in my patent No. 787,012, of April 11, 1905. As this, however, forms no part of the present invention, it is not illustrated in the drawing.

B is a storage battery in a branch circuit, whose terminals are connected to the terminals of the main generator.

C C represent the main or lighting circuit in which are situated the lamps C' of the car. 70 In the main circuit C is the armature D of the crusher. This crusher is driven by a motor whose armature E is connected in shunt between the points 1 and 2 of the circuit. This motor will, therefore, receive the variations 75 of voltage of the main generator.

F is the armature of an exciter for the field D' of the crusher, this exciter armature and crusher field being connected in series in a separate branch between the points 1 and 2. 80 The field magnet E' of the motor is wound so as to be substantially saturated at all expected voltages. This is diagrammatically indicated in the drawing by the construction of the core of the magnet. On the other hand, 85 the field magnet F' of the exciter is wound so as to at all times have a low density.

G represents the usual safety switch in the generator circuit between the points 1 and the battery junction with the main circuit, this switch being normally maintained closed by the shunt coil g and the series coil g'.

In operation when it is desired that the main generator shall be in service with the crusher outfit, a switch as h may be closed, thus connecting the motor and the exciter and the crusher field in their respective circuits. When the voltage of the main dynamo has risen to a predetermined value, the coil g will close the switch G and the current from the generator will pass over the circuit and charge the batteries as well as provide current for the lamps if they are in circuit. If at any time there should be a reverse current from the batteries to the generator, this current passing through the coil g' neutralizes the pulling effect of the coil g and switch G opens. As soon as the voltage of the main generator rises sufficiently to charge the batteries in the branch circuit, there will be too 110

high a voltage for the efficient operation of the lamps in the main circuit so that an opposing voltage is desired at the crusher D. The apparatus is so designed that with a voltage of dynamo A equal to that desired at the lamps the speed of the crusher outfit will be such that the exciter F will produce a voltage exactly equal to that of the generator A. Upon an increase of voltage, however, the motor E will correspondingly increase in speed, its field magnet strength being at all times the same, or substantially so, and, therefore, the exciter will correspondingly increase in speed and will increase in voltage at a rate greater than that of its change of speed, because its field magnet is at a low density. The result will be that the crusher field D will receive a current which will act upon the crusher to produce a voltage opposing that of the main generator. By proper design of the apparatus the variation of voltage of the exciter taken with the variation of the speed of the crusher will cause the crusher to produce an opposing electro-motive-force exactly equal to the increase of voltage on the main generator. Thus the voltage of the main circuit remains unchanged.

By my invention the voltage can be varied in the branch circuit containing the battery B to any desired extent while automatically maintaining the desired voltage across the lamp circuit C. I find that this results in a thoroughly satisfactory car lighting system where the maintenance of a constant voltage on the main circuit is a most important advantage.

Having thus described my invention what I claim as new and desire to secure by Letters Patent is:

1. In a car lighting system the combination of a variable speed dynamo generator, a main or lighting circuit and lamps connected therewith, a battery connected to the dynamo generator, a dynamo crusher in the main circuit between the lamps and the junction of the battery and dynamo generator, a motor connected across the circuit on the generator side of the crusher and arranged to be variable in speed in accordance with the voltage variations of the dynamo generator, and means for varying the voltage of the crusher in accordance with the varying speed of said motor.

2. In a car lighting system the combination of a variable speed dynamo generator, a main or lighting circuit and lamps connected therewith, a battery connected to the dynamo generator, a dynamo crusher in the main circuit between the lamps and the junction of the battery and dynamo generator, a motor connected across the circuit on the generator side of the crusher and arranged to be variable in speed in accordance with the voltage variations of the dynamo generator and a field regulating dynamo for the

crusher mechanically connected to the said motor.

3. In a car lighting system the combination of a variable speed dynamo generator, a main or lighting circuit and lamps connected therewith, a battery connected to the dynamo generator, a dynamo crusher in the main circuit between the lamps and the junction of the battery and dynamo generator, a motor connected across the circuit on the generator side of the crusher and arranged to be variable in speed in accordance with the voltage variations of the dynamo generator, and a field regulating dynamo for the crusher mechanically connected to the said motor, the armature of said field regulating dynamo being connected in series with the crusher field winding in a branch across the system.

4. In a car lighting system the combination of a variable speed dynamo generator, a main or lighting circuit and lamps connected therewith, a battery connected to the dynamo generator, a dynamo crusher in the main circuit between the lamps and the junction of the battery and dynamo generator, a motor connected across the circuit on the generator side of the crusher and arranged to be variable in speed in accordance with the voltage variations of the dynamo generator, a field regulating dynamo for the crusher having its armature connected in series with the crusher field winding in a branch across the system, and mechanical connections between the crusher, the motor and the field regulating dynamo.

5. In a car lighting system the combination of a variable speed dynamo generator, a main or lighting circuit and lamps connected therewith, a battery connected to the dynamo generator, a dynamo crusher in the main circuit between the lamps and the junction of the battery and dynamo generator, a motor connected across the circuit on the generator side of the crusher and arranged to be variable in speed in accordance with the voltage variations of the dynamo generator, and having a substantially constant field strength, and a field regulating dynamo mechanically connected to said motor and in series with the field winding of the crusher in a branch across the system, and having a low density field magnet.

6. In an electrical system of distribution a source of electrical energy, a main or lighting circuit, a battery connected to the source of electrical energy, a crusher in the main circuit between the load and the junction of the battery and source of electrical energy, a shunt motor connected in parallel with the load and crusher and arranged to be variable in speed in accordance with the voltage variations of the source of electrical energy, and a field regulating shunt dynamo mechanically connected to said motor and in a circuit parallel with it, said circuit containing the field

winding of the crusher in series with said dynamo.

7. In a car lighting system, the combination of a variable speed main dynamo, a main lighting circuit and lamps connected therewith, a battery connected to the dynamo, a dynamo crusher in the main circuit between the lamps and the junction of the battery and the main generator, a motor connected across the circuit on the generator side of the crusher for operating the crusher and a field regulating dynamo for the crusher mechanically connected to said shunt motor and in series with the field winding of the crusher in a branch across the system, said field regulating dynamo being so wound as to vary in voltage in excess of the variations in voltage of the main dynamo.

8. In a car lighting system the combination of a main generator, a main lighting circuit, a battery connected to the main generator, a dynamo crusher in the main circuit between the lamps and the junction of the battery and the main generator, a motor connected across the circuit on the generator side of the crusher for operating the crusher and a field regulating dynamo for the crusher adapted to vary in voltage in accordance with the voltage variations of the main generator.

In testimony whereof, I have signed my name to this specification, in the presence of two subscribing witnesses.
